UNITED STATES PATENT OFFICE.

HARRY D. WEED, OF THE UNITED STATES ARMY.

BOMB-CARRYING GEAR.

1,311,630.

Specification of Letters Patent. Patented July 29, 1919.

Application filed June 7, 1919. Serial No. 302,586.

(FILED UNDER THE ACT OF MARCH 3, 1883, 22 STAT. L., 625.)

To all whom it may concern:

Be it known that I, HARRY D. WEED, of the United States Army, a citizen of the United States, stationed at McCook Field, 5 Dayton, Ohio, have invented an Improvement in Bomb-Carrying Gear, of which the following is a specification.

The invention described herein may be used by the Government, or any of its officers or employees in prosecution of work 10 for the Government, or by any other person in the United States, without payment of any royalty thereon.

This invention relates to a bomb carrying 15 gear for airplane bombs.

It is an important object of this invention to provide a simple, strong and light carrying gear for bombs so designed that the bomb is hung from a point above and to one 20 side of a bearing for the side of the bomb, whereby the weight of the bomb will cause the side thereof to bear against the bearing and so prevent any vibration of the bomb while the airplane is in flight. The above 25 described arrangement does not in any way interfere with the release of the bomb.

It is a further object of this invention to provide a main supporting rib on which two bombs may be hung and four bearing surfaces 30 for the sides of the bombs, two of said surfaces being located below and to one side with respect to said rib, the other two of said surfaces being located below and on the opposite side with respect to the said rib, 35 whereby the sides of the bombs, due to their own weight, bear against said bearing surfaces in opposite directions and so balance each other.

It is a further object of this invention to 40 provide a truss support for the said bearing surfaces.

It is a further object of this invention to provide a supporting rib on which two bombs may be hung and which is shaped 45 substantially like an inverted V. The bombs are so hung with relation to this rib that the pull due to the weight of the bombs is substantially parallel to the respective legs of said inverted V-shaped rib. This gives an

extremely stiff and rigid support, with a 50 minimum of weight.

Other objects and advantages will appear as the description proceeds.

In the drawings illustrating one embodiment of my invention, Figure 1 is a side 55 view of my bomb carrying gear.

Fig. 2 is an end view of the same.

Fig. 3 is a section on the line 3-3 of Fig. 2.

Fig. 4 is a view partly in section of the 60 releasing mechanism.

Figs. 5 and 6 are sectional views of the releasing mechanism, showing successive stages of operation.

Fig. 7 is a perspective view of the sup- 65 porting rib and associated parts.

Fig. 8 is a section of the same taken on the line 8-8 of Fig. 3.

Fig. 9 is a section of the same taken on the line 9-9 of Fig. 3. 70

The bomb carrying gear comprises a pair of horizontally extending supports, extending transversely with respect to the path of the airplane. These supports are substantially parallel to one another, the forward 75 one being indicated at 1 and the rear one at 2. These supports are stream lined to minimize air resistance.

The supports 1 and 2 are supported from beams 3, suitably attached to the body or 80 plane 4 of the airplane.

A pair of substantially U-shaped brackets 5 and 6 supported by bolts 7 from the front support 1 inclose between them the end of the main supporting rib 8, which is shaped 85 like an inverted V. The rear end of the rib 8 is supported from the support 2 by precisely similar means. The brackets 5 and 6 and the end of the rib 8 are bonded together by being dip brazed. 90

A pair of arcuately shaped hangers 9 and 10 are positioned in suitable apertures through each of the legs of the rib 8 and are rigidly held in position by cotter pins 11, and by dip brazing. The parts 5, 6 and 95 9 may be dip brazed by the same operation.

The rib 8 is provided with a pair of longitudinally extending slots 12. A trigger ac-

tuating plate 13, provided with an outwardly bent trigger engaging end 14, is attached to a second sliding plate 15, the two plates being connected together by lugs 14, said lugs 5 passing through the slot 12 and being formed as a part of the plate 15, and held in engagement with slide 13 by cotter pins. Each of the slides 15 has attached thereto a spring 16, the other end is attached to a 10 pin 17 fastened to the rib 8, to keep the slides 13 and 15 to the right, as shown in Fig. 1. Each of the slides 15 has attached at its other end an actuating rod 18, controlled by levers 19 and 20, which in turn 15 are controlled by manual operating means, not shown.

The front bearing for the bomb will now be described. This bearing comprises vertically disposed bearing surfaces 21 and 22 20 preferably made integral with a connecting piece 23. These bearing surfaces are supported by a V shaped element 24, which is attached to the support 1 by bolts 25, and which, at its apex is attached to the connecting piece 23. A compression element 26 25 is positioned between the apex of the V shaped element 24 and the support 1 to complete the truss support for the bearing surfaces. An additional brace 27, engages with 30 the bearing surfaces 21 and 22. A precisely similar set of bearing surfaces and supporting truss are provided toward the rear end of the bomb carrying gear, as shown in Fig. 1. The two trusses may be 35 braced apart by the element 28.

It should be noted that the bearing surfaces 21 and 22 are located below and to one side with respect to the rib 8.

The means for attaching the bomb to the 40 rib 8 will now be described. This connecting means or hanger comprises an elongated body element 29, made by bending a sheet of metal into substantially U-shaped form, the bight of the U being indicated at 30.

45 The metal forming the ends of the element 29 has its upper parts fastened together as indicated at 31 and 32. Apertures 33 and 34 are punched through the respective portions 31 and 32. It should be 50 noted that these said apertures are spaced unequally from the ends of the element 29. These said apertures are adapted to engage over the ends of the arcuate elements 9 and 10. It should be noted that the arcuate elements 55 9 and 10 are also correspondingly and unequally spaced from the respective ends of the rib 8, being so arranged however that if the element 29 is engaged with the arcuate elements 9 and 10 right side up, the apertures 33 and 34 will properly fit over said elements 9 and 10, but if element 60 29 is attempted to be engaged on elements 9 and 10 wrong end to the said apertures will not engage over said elements 9 and 10, 65 and so the improper mounting of the ele-

ment 29 on the rib 8 is automatically prevented. The hanger 29 is held in place on the elements 9 and 10 by cotter pins 9' and 10', respectively.

A pair of bomb carrying hooks 35 and 36, 70 pivoted respectively at 37 and 38 in said hanger 29, are further pivoted at their respective upper ends at 39 and 40 to a bar 41, which bar is movable longitudinally with respect to the hanger 29, between the sides 75 thereof. The lower part of the hooks 35 and 36 are adapted to engage rings 42 and 43 attached to the bomb. It will be apparent that the heavy weight of the bomb acting on the lever hooks 35 and 36, will tend to move 80 the upper arms of said hooks to the left, and will consequently tend to move bar 41 to the left.

A locking sear 44 is pivoted to the bar 41 at 45 and is normally urged downwardly by 85 spring 46 bearing against it and against an upper edge of the bar 41. The sear 44 is provided with a shoulder 47 that normally is engaged over an edge of a stop 48 rigidly mounted to the hanger 29. When the parts 90 are engaged as in Fig. 4 it is apparent that the bombs will be effectively held against release.

A trigger 49 is pivoted to the hanger 29 at 50, is provided with a cam face 51 that 95 bears against the lower edge of the sear 44, and is further provided with a notch 52, which overhangs the end 53 of the sear 44 and acts as a safety catch in case of failure of spring 46. The trigger 49 is urged to the 100 left by a spring 54. The described parts are so proportioned and shaped that when the trigger 49 is moved to the right, notch 52 is first moved from the path of the end 53 of the sear, after which the cam surface 51 105 lifts the sear 44 from engagement with the stop 48, whereupon the bar 41 is released and moves to the left to release the bomb, a sequence of operation clearly shown in 110 Figs. 5 and 6.

The trigger 49 is actuated through the already described lever 20, rod 18, slide 14 and lug 15, Figs. 1 and 3, or it may be actuated by a wire or cable fastened thereto in 115 the aperture 49'.

It should be understood that each rib 8 carries two hangers 29, as shown in Fig. 2 and so supports two bombs.

It should also be noted that the line of pull due to the weight of the bombs, these 120 bombs being indicated by dotted lines in Fig. 2, is a diagonal line substantially parallel each to its adjacent leg of the rib 8, and in such a direction as to cause the sides of the two bombs to bear, at the front and rear thereof against the respective front and rear bearings 21 and 22, whereby vibration of the bombs is prevented, and yet no interference is had to the free fall of the bombs when released.

The hanger 29 and associated release mechanism forms the subject of a separate application, Serial No. 302,585, filed June 7, 1919.

5 While I have illustrated a particular embodiment of my invention it should be understood that it may be carried out in other ways as defined within the scope of the following claims.

10 I claim as my invention:—

1. In a bomb carrying gear, a rib element, means for detachably engaging a bomb with said rib element and a bearing element for the side of a bomb, positioned 15 below and to one side with relation to said rib, so that the weight of the bomb causes the side thereof to bear against said bearing element.

2. In a bomb carrying gear, a rib element, 20 a bearing element for the side of a bomb, located below and to one side with relation to said rib element, and means extending downwardly and outwardly with relation to said rib element to detachably engage a 25 bomb with said rib element.

3. In a bomb carrying gear, a rib element, means supporting said rib element at its ends, two bearing means for the side of a bomb, located below the respective ends of 30 said rib element and to one side with respect to said rib, and means for detachably engaging a bomb with said rib.

4. In a bomb carrying gear, a pair of transversely extending, horizontally disposed supports, a rib element attached to and extending from one support to the other, bearing means for the side of a bomb carried by each of said supports, said bearing means being located below and to one 35

side with respect to said rib element, and means to detachably engage a bomb with 40 said rib element.

5. In a bomb carrying gear, a pair of transversely extending, horizontally disposed supports, a rib element attached to 45 and extending from one support to the other, bearing means for the side of a bomb carried by each of said supports, said bearing means being located below and to one side with respect to said rib element, each 50 bearing means being supported by a truss from its respective support, and means to detachably engage a bomb with said rib element.

6. In a bomb carrying gear, for a pair of 55 bombs, a pair of transversely extending, horizontally disposed supports, a rib element attached to and extending from one of said supports to the other, bearing means carried by said supports, for the inner sides 60 of a pair of bombs, said bearing means being located below and to one side with respect to said rib and symmetrically disposed with respect thereto and means for detachably engaging a pair of bombs to said 65 rib.

7. In a bomb carrying gear, a pair of supports, a rib element carried thereby, said rib element being shaped substantially like an inverted V, bearing means for the side 70 of a bomb located below and to one side with relation to said rib element, and means to detachably engage a bomb with said rib element, whereby the weight of the bomb is transmitted to said rib in a line substantially parallel to one of the legs of said inverted V. 75

HARRY D. WEED.
